(57) **CLAIM**

The ornamental design for a handle of a box, as shown and described.

DESCRIPTION

FIG. 1 is a front perspective view of a handle of a box showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof;

FIG. 7 is a rear perspective view thereof, the circled areas shown enlarged for completeness of disclosure; and,

FIG. 8 is a perspective view thereof, the box shown in broken lines for illustrative purposes only and forms no part of the claimed design.
